FLUSH VALVE

Winnifred A. Stout, Stockton, Calif.

Application October 5, 1934, Serial No. 747,067
Renewed May 6, 1936

7 Claims. (Cl. 137—93)

My present invention relates generally to flushing devices and more particularly to that type of device which includes a pressure seated piston and manually opened valve substantially remote from the piston and controlling an outlet channel which, when the valve is open, ports the pressure chamber into the outflow channel.

The primary object of my invention is the provision of an arrangement of the above type in which the working parts are so arranged as to be readily accessible for purposes of repair, adjustment or replacement of parts, and to promote simplicity, effective action and augmented life.

Further and more specific objects of my invention will appear in the course of the following detailed description of its construction, operation and advantages, reference being had to the accompanying drawing, which forms a part of this specification, and in which

Figure 1 is a vertical sectional view through my improved flushing device;

Figure 2 is a horizontal section taken substantially on line 2—2 of Figure 1, and,

Figure 3 is a bottom plan view of the piston.

Referring now to these figures, my improved device comprises an open top casing 10 having inflow and outflow passages 11 and 12 respectively, and an internal cylindrical wall 13, forming an inner continuation of the outflow passage. The wall 13 opposes in spaced relation and extends above the inner end of the inflow passage 11.

Communication between the inflow and outflow passages is controlled by a piston 14 in a piston cylinder 15 of substantially greater diameter than the wall 13 and open at each end. The lower portion of cylinder 15 encompasses in spaced relation the upper part of wall 13. The lower end of cylinder 15 is mounted, below the upper end of wall 13, upon an internal annular seat 15^a formed on the inner face of casing 10.

The upper end of cylinder 15 is engaged and held by a cap 16 which also closes the open top of casing 10. The cap 16 includes a rim 16^a having a reduced peripherally threaded part 16^b, a peripheral shoulder 16^c formed with a depending annular flange 16^d coacting with the upper portion of part 16^b to form an annular pocket 16^e in which is arranged a washer 16^f. The reduced part 16^b depends into the open upper end of casing 10 and has threaded engagement with the inner face of the latter. The casing 10 extends into pocket 16^e and has its top edge bearing against washer 16^f. The casing 10 and rim 16^a of cap 16 are spaced from cylinder 15. The cap 16 coacts with the seat 15^a for holding

the cylinder 15 stationary. The cap 16 is formed with an axial threaded bore to receive an adjusting screw 17 extending downwardly into the cylinder 15 to limit upward movement of the piston 14, and a cap screw 18 to normally prevent tampering with the adjusting screw 17.

The cylinder 15 in connection with the adjacent portion of casing 10 and rim 16^a of the cap 19 provides a pressure chamber 19 which communicates at its upper end with the upper portion of cylinder 15 for the supply of pressure into the latter above and against piston 14. A pressure inlet forming means or port 20 is mounted in the body of casing 10 inwardly adjacent to the outer end of inflow passage 11. The means 20 is permanently open and establishes communication between the inflow passage 11 and chamber 19. The body of casing 10 is formed diametrically opposite the means 20 with a permanently open pressure outlet port 21 leading downwardly, from chamber 19 and opening into the inner end of a cylindrical side valve chamber 22 open at its outer end, closed at its inner end and formed from an integral part of the body of casing 10.

The outer portion of valve chamber 22 is enlarged, thereby providing therein an outwardly facing annular shoulder 23 against which is arranged a seating ring 23^a. Seated against ring 23^a is the inner end of a valve cage or plug 24 formed at its outer end with an annular flange 24^a abutting casing 10. The plug 24 constitutes a closure for chamber 22 and also a combined support and guide for a spring controlled piston relief valve 29. The inner portion of the plug 24 is spaced from the enlarged portion of the valve chamber 22 and from the space 24^b between the said portions a channel 25 leads to the outflow passage 12.

The outer portion of plug 24 threadedly engages with the wall of chamber 22. The plug 24 has a pocket 24^c opening at its outer end and a pocket 27 opening at its inner end. The pocket 27 opens into the inner or portion of smallest diameter of chamber 22. The socket 24^c is of greater diameter and depth than that of pocket 27. The plug 24 has an axial bore 27^a which connects the pockets together. The plug 24 is provided with a channel 28 which leads from pocket 27 to the space 24^b and has its discharge end align with the intake end of channel 25. Extending through the pockets and said bore is a spring controlled valve stem 26 having its inner end projected into the inner portion of valve chamber 22.

The valve 29, secured upon the inner end of

stem 26, normally seats flatwise against the inner end of plug 24 and thus prevents communication between the inner portion of valve chamber 22, as well as the lower end of port 21, with the outlet channel 25. For this purpose, the outer end of stem 26 has an enlarged head 30 and a coil spring 31 is mounted on stem 26 between the base of pocket 24^c and the head 30.

A cap 32 is threaded upon the external surface of the wall of valve chamber 22 and extends beyond the head 30, with its outer end apertured for the reception of an operating handle 33 having an inner head 34 with a flat face contacting the outer face of the valve stem head 30 so that angular movement of handle 33 in any direction will force the valve stem inwardly and unseat the valve 29.

When, in operation, the valve 29 is unseated as above, the pressure chamber 19 is thus vented through port 21, valve chamber 22 and channel 25 to the outflow passage 12, so that pressure on top of the piston 14 is thus relieved and the latter is moved upwardly off of the upper end of the wall 13, by the water rushing from the inflow passage 11 which by this means freely passes out through the outflow passage 12. When handle 33 is released and valve 29 permitted to resume its normal closed position the outlet of the pressure chamber is cut off and pressure immediately begins building up therein due to the forcing of water from the inflow passage through the port 20. This pressure soon reaches the point where, since it is confined, it overcomes the pressure of the water against the lower face of piston 14 and forces the latter downwardly onto the upper end of internal wall 13 cutting off the flushing action.

40 It will be noted that the piston 14 is of special construction and in a single piece, with a body, cylindrical in form, of rubber substantially harder than its lower circular rib 35. The relatively soft rib 35 acts as a valve, seating on the upper edge of internal wall 13, and the relatively stiff body of piston 14 is reinforced by an embedded metallic disc 36 and has a dished or concave peripheral face and upper and lower lips 37 around 45 its peripheral edges, whose outer surfaces co-operate with the cylinder 15 in the movements of the piston. The lower lips 37 extend downwardly beyond and encompass in spaced relation 50 the rib 35.

While my invention is ideally adapted to the uses of a flush valve where the amount of water delivered per unit of time in active operation is not a point of great nicety, it is suited equally well to uses where such amount of flow must be regulated with great accuracy, as, for example, when it is used as an instrument for the accurate measurement and delivery of fluids other than water. It will be readily seen that by operating the handle 33 at definite intervals and durations thereof, automatically or otherwise, while maintaining a constant head of the fluid entering the inlet passage, and suitably adjusting the screw 17, the result will be periodic discharges from the outlet passage of sensibly equivalent amounts of fluid. I desire it understood, therefore, that I do not wish to confine myself to the interpretation of my invention merely as a flush valve, but desire protection for such other uses as it is well adapted to serve and ask that my claims be interpreted upon that basis.

What I claim is:

75 1. In a flushing device having inflow and outflow passages and a pressure chamber having an inlet port opening into the inflow passage and an

outlet port opening into the outflow passage, and a valve controlling said outlet port, a piston normally seated to close the outflow passage and exposed at one face to the inflow passage and at its opposite face to the pressure chamber, and a cylinder in which said piston works, said piston having its body formed of compressible resilient material having a seating rib on its active face of greater resiliency than the remaining portion of said body, said body being formed at its ends with annular lips extending in opposite directions therefrom and forming portions of its cylinder-engaging periphery. 5 10

2. In a flushing device having inflow and outflow passages and a pressure chamber having an inlet port opening into the inflow passage and an outlet port opening into the outflow passage, and a valve controlling said outlet port, a piston normally seated upon and closing the intake end of said outlet passage, said piston being exposed at one face to the inflow passage and having its opposite face subjected to pressure from said chamber, and a cylinder in which said piston works and communicating with said chamber, said piston having its body formed of compressible resilient material of different degrees of softness, the seating portion thereof being materially softer than any other part of the piston, and the said body being provided at its ends with annular flared lips extending in opposite directions therefrom for engagement with the inner face of said cylinder, one of said lips encompassing in spaced relation and extending beyond said seating portion.

3. In a flushing device having inflow and out-flow passages and a pressure chamber having an inlet port opening into the inflow passage and an outlet port opening into the outflow passage, the intake end of said outflow passage being arranged above the inner end of said inflow passage, a valve controlling said outlet port, a piston normally seated on said intake end to close the outflow passage and exposed at one face to the inflow passage and at its opposite face for the application of pressure from said chamber, and a cylinder in which said piston operates communicating with said chamber, said piston having its body formed of compressible resilient material having that part seating upon said intake end of greater resiliency than the remaining part thereof, said body being formed at its ends with flared annular lips extending in opposite directions therefrom to engage the cylinder wall, the said body being provided with a deformation-resisting member of harder and less resilient material than the remainder of the body. 50 55

4. In a flushing device having inflow and outflow passages and a pressure chamber having an inlet port opening into the inflow passage and an outlet port opening into the outflow passage said 60 outflow passage having an intake end above the inner end of the inflow passage, a shiftable spring controlled valve controlling said outlet port, a piston normally seated on said intake end to close the outflow passage and exposed at one face 65 to the inflow passage and at its opposite face for the application of pressure from said chamber, and a cylinder in which said piston operates and for receiving pressure at its upper end from said chamber for application upon the piston, said 70 piston having its body molded as a unit of semi-hard rubber with a soft rubber seating rib on that face thereof exposed to the inflow passage, and with flared annular lips at its ends extending in opposite directions therefrom and forming port- 75

tions permanently engaging with the cylinder wall.

5. In a flushing device having inflow and outflow passages and a pressure chamber having an 5 inlet port opening into the inflow passage and an outlet port, a piston normally seated on and closing the intake end of the outflow passage and exposed at one face to the inflow passage and at its opposite face for the application of pressure 10 from said chamber, a shiftable spring controlled valve normally closing said outlet port, and a cylinder in which said piston operates and for receiving pressure at its upper end from said chamber for application upon the piston, said 15 piston having its body molded as a unit of semi-hard rubber and a soft rubber seating rib on that face exposed to the outflow passage and annular flared lips extending in opposite directions from its ends to permanently engage the cylinder wall, 20 and said piston having its body provided with an embedded deformation-resisting member of a relatively stiff non-yielding material.

6. In a flushing device a casing being formed 25 to provide an inflow passage, an outflow passage including an upstanding cylindrical wall forming portion arranged in close spaced relation to and extending above the inner end of the inflow passage and a valve chamber spaced from and disposed at right angles to said wall forming portion, 30 the upper end of said wall forming portion providing an intake for said outflow passage, a cylinder supported on its lower end within and by the casing and having its lower portion encompassing in spaced relation the upper part of said 35 wall forming portion, a part of the lower end of said cylinder arranged outwardly with respect to the inner end of said inflow passage, said cylinder providing a piston chamber, said cylinder and casing coacting to provide a pressure receiving 40 chamber communicating with the piston chamber and having a permanently open inlet leading from said inflow passage and an outlet leading to said valve chamber, a piston operating in said cylinder normally seating on the top of said wall forming 45 portion for closing said outflow passage, said piston having its lower face exposed to the inflow passage and its upper face for application of

pressure from the pressure receiving chamber to normally maintain the piston seated, said casing being formed with a channel leading from said valve chamber to said outflow passage, and a valve structure connected to the casing and extending into said valve chamber, said structure including a shiftable spring controlled valve for normally closing the valve chamber to said channel. 5

7. In a flushing device a casing formed to provide an inflow passage, an outflow passage including an upstanding cylindrical wall forming portion arranged in spaced relation to and extending above the inner end of the inflow passage and a valve chamber spaced from said wall forming portion, the upper end of said wall forming portion providing an intake for said outflow passage, a cylinder supported within the casing and having its lower portion encompassing in spaced relation the upper part of said wall forming portion, said 20 cylinder providing a piston chamber, said cylinder and casing coacting to provide a pressure receiving chamber communicating with the piston chamber and having an inlet leading from said inflow passage and an outlet leading to said valve 25 chamber, a piston operating in said cylinder and normally seating on the top of said wall forming portion for closing said outflow passage, said piston having its lower face exposed to the inflow passage and its upper face for application of 30 pressure thereon from the pressure receiving chamber to normally maintain the piston seated, said casing being formed with a channel leading from said valve chamber to said outlet passage, a valve structure connected to the casing and extending into said valve chamber, said structure including a shiftable spring controlled valve for normally closing the valve chamber to said channel, and said piston formed of a resilient body provided with oppositely disposed flared annular 35 lips permanently bearing against the wall of said cylinder, said piston having its lower face formed with an annular rib of greater resiliency than the remaining portion of the piston for seating on the upper end edge of said upstanding wall forming 40 portion. 45
